DEWAXING WITH EVAPORATIVE COOLING

Edwin C. Knowles, Beacon, N. Y., assignor to The Texas Company, New York, N. Y., a corporation of Delaware

Application March 3, 1937, Serial No. 128,702

4 Claims. (Cl. 196—18)

This invention relates to the dewaxing of mineral oil.

In my co-pending application Serial No. 41,393, there is disclosed and claimed the dewaxing of mineral oil in the presence of naturally occurring or added wax crystal modifiers, in which the wax-bearing oil containing such modifier together with solvent is heated to a supersolution temperature which is substantially above the temperature of complete wax solution in order to condition the wax bearing oil for wax separation. This causes upon chilling precipitation of wax in a form which gives very substantial increase in filtration rates upon filtering the precipitated wax from the oil. This mentioned application also discloses the advantage of avoiding substantial mechanical agitation during chilling so as to avoid objectionable alteration of wax crystal structure with resultant lowering in filtration rates.

It is an object of the present invention to provide an improved method of and apparatus for dewaxing mineral oil, utilizing the features of my above mentioned co-pending application, and effecting chilling of the wax-bearing oil in a novel and highly efficient manner while avoiding any substantial mechanical agitation.

It is a further object of the present invention to utilize dewaxing solvents, or solvent mixtures, which are normally liquid at atmospheric temperatures and pressures, and to obtain partial chilling of the wax-bearing oil by the flashing of such oil into a high vacuum zone under such conditions that substantial evaporation or distillation of the normally liquid solvent occurs.

It is a further object of the present invention to provide additional thermal economy in chilling by the use of pre-chilled solvent, preferably solvent which has been recovered by condensation of solvent vapors liberated in the evaporative cooling of previous charges of wax-bearing oil.

It is still another object of the invention to provide a dewaxing process of this character enabling a comparatively low solvent dilution ratio to be employed, and to effect substantial thermal economy by a combination of chilling with pre-chilled solvent and evaporative cooling, with cyclic recirculation of solvent from the evaporative cooling for reuse as additional pre-chilled solvent.

Other objects and advantages of the present invention will be apparent from the following description taken in conjunction with the accompanying drawing and appended claims.

15 In accordance with the method of the present

invention, the wax-bearing oil to be dewaxed is diluted with a suitable dewaxing solvent or solvent mixture which is normally liquid at atmospheric temperatures and pressures. Examples of suitable solvents or solvent mixtures adapted for use in accordance with the present invention are methyl ethyl ketone and benzol, acetone and benzol, acetone, benzol and toluol, and methyl ethyl ketone and isopropyl ether. It is to be understood that these solvent combinations are given by way of illustration only, and that other solvents and solvent combinations known for dewaxing and which are normally liquid at atmospheric temperatures and pressures can be employed. The wax-bearing oil may be of the type containing naturally occurring modifiers, such as are found in residual oils or in heavy distillate lubricating oils having a Saybolt Universal viscosity at 210° F. in excess of about 75 seconds. Or the oil may contain added wax crystal modifiers of the character of montan wax and aluminum stearate, condensation of polymerization products such as those obtained by condensation of halogenated waxy hydrocarbons, distillation residues or coal tar and mineral oil products, and other well-known wax crystallization aids of this character. While the invention is particularly described in connection with the use of such a wax crystal modifying material, it is to be understood that features of the invention including the use of pre-chilled solvent and evaporative cooling by flash distillation are not confined to the employment of oils containing such wax crystal modifying materials, but are useful generally in the dewaxing of mineral oil.

The oil diluted with solvent in the ratio of say 2-3 parts of solvent to 1 of oil is heated to a supersolution temperature of the order of about 160° F.—200° F. in order to condition same for wax crystallization. This oil mix is then shock-chilled, as by water-cooled heat exchangers to a temperature of the order of 100-130° F. or somewhat above the temperature of incipient wax precipitation. This partially cooled oil mix is then further chilled by mixing with a quantity of pre-chilled solvent, thereby raising the dilution ratio at the time of incipient wax precipitation. For example, the oil mix at a temperature of around 100-130° F. may be mixed with an additional quantity of the dewaxing solvent at a temperature of about 30-50° F. or below in the proportion of three volumes of oil mix to one volume of solvent. In the case where the original wax-bearing oil had been diluted with two volumes of solvent to one volume of oil, this

would raise the dilution ratio to 3:1, while at the same time rapidly chilling the oil mix by direct heat exchange and mixing with the added pre-chilled solvent. It is to be understood that the use of pre-chilled solvents for effecting partial chilling of the oil mix may be employed in other portions of the chilling range; but this is found particularly useful in lowering the temperature of the oil mix to or somewhat beyond that of incipient wax precipitation, as this has a beneficial effect on wax crystal structure.

The oil mix is then passed through an expansion valve and spray nozzle into a distillation chamber or tower maintained under a high vacuum equivalent to an absolute pressure of about 5-10 mm. mercury or less. Under these conditions a fine spray of the solvent oil mix is formed and a substantial proportion of the solvent will be vaporized with resultant evaporative cooling of the remaining oil mix. This will serve to lower the temperature of the oil mix throughout the greater portion of the range of wax precipitation and thereby accomplish chilling without any substantial mechanical agitation of the type which has been found to be injurious to wax crystal structure. The use of evaporative cooling in conjunction with normally gaseous solvents has been heretofore suggested, but this requires pressure equipment in which the oil-solvent mix is maintained under high pressure to maintain the solvent in the liquid state, and a portion of the solvent is then allowed to escape or vaporize by release of a portion of the super-atmospheric pressure applied thereto. The present process is distinguished by the employment of normally liquid dewaxing solvents which can be handled throughout the major portion of the equipment in ordinary atmospheric tanks and piping, and by then flashing the oil mix into a zone of high vacuum in the manner of flash distillation.

Depending upon the character of the solvent employed, the temperature of the oil mix in the flash distillation vacuum zone may be lowered very substantially, such as to a temperature of the order of 0° F., minus 20° F. or below. The chilling of the oil mix to a filtration temperature of the order of -10 to -20° F. may then be carried out in the customary double pipe chiller without objectionable alteration or destruction of the wax crystal structure. By thus chilling the oil through the major portion of the range of wax crystallization without mechanical agitation, it is found that the final chilling to the filtration temperature can be accomplished in comparatively small sized conventional chilling equipment without substantial reduction in filtration rates of the chilled mix due to alteration in wax crystal structure. The chilled oil mix is then filtered in the usual manner to separate the wax from the oil, as by the use of continuous rotary filters, pressure filters or filter presses.

The oil filtrate is preferably passed in heat intertangue relationship with the solvent vapors released from the flash distillation zone in order to condense the major portion of these vapors. Remaining uncondensed vapors pass to the vacuum producing equipment for the flash distillation zone, and are then discharged through additional condensing equipment, wherein the oil filtrate may be further employed as the cooling medium, to condense the remaining solvent vapors. The recovered solvent condensate at a low temperature is then recycled to the dilution step where the oil mix is diluted with pre-chilled solvent.

vent. The filtrate oil after passing through the solvent vapor condensing equipment to utilize the chilling effect thereof is then passed to solvent strippers where the solvent is separated from the dewaxed oil in the usual manner.

Referring to the drawing, which illustrates preferred embodiments of apparatus for carrying out the method of the present invention,

Fig. 1 is a diagrammatic illustration of apparatus in which a single stage of flash distillation is employed; and Fig. 2 is a partial diagrammatic illustration of a modification in which a plurality of successive flash distillation stages are employed.

As shown in Fig. 1, the charge of oil-solvent mix is introduced by line 10 to a steam heater 11 where the mix is heated by closed steam coils to a supersolution temperature. By way of example, the oil may be diluted in a 2:1 dilution ratio with a solvent mixture of 50% methyl ethyl ketone and 50% benzol. The mix is heated to a temperature of the order of 170° F., which is found to condition the oil in the presence of naturally occurring or added wax crystal modifiers for subsequent wax precipitation in a form which materially increases the filtration rate upon separation of the wax from the chilled oil in the subsequent wax filtration step. The heated oil mix is then passed by line 12 through a water or air-cooler 13 where the mix is shock chilled to a temperature of the order of 120° F. The partially chilled mix is then passed by line 14 to a mixing jet or nozzle 15 into which is introduced additional solvent by line 16. For example, one volume of mixed solvent consisting of 50% methyl ethyl ketone and 50% benzol at a temperature of about 40° F. may be added at this point to the three volumes of oil mix coming from the water coolers. Nozzle 15 discharges into an atmospheric tank 17, wherein the diluted oil mix accumulates at a temperature of about 100° F. and in a dilution ratio of three volumes of solvent to one of oil under the conditions set forth above. The oil is thereby chilled by the use of pre-chilled solvent to the temperature of incipient wax precipitation.

The partially chilled mix is then passed by one of branch lines 21, 22 and 20 containing shut-off valves 24, 25 and 26 respectively into one of flash distillation chambers or towers 27, 28 or 29. Preferably each flash distillation chamber is constructed as a cylindrical smooth wall tower of substantial height without interior filling or trays. The branch lines 21, 22 and 20 are provided with expansion valves and spray nozzles 30, 31 and 32 respectively, located just at the point of introduction into the top of towers 27, 28 and 29 respectively. The spray nozzles may be arranged to direct the incoming charge in a tangential direction to produce a swirling movement of the charge therein. Or the charge may be directed against vanes, baffles or other forms of atomizers to assist the evaporation within the flash towers. The towers are equipped with vapor off-takes 33, 34 and 35 respectively provided with shut-off valves 36, 37 and 38. Each of these vapor off-takes serves to introduce the vapors into the lower portion of a baffled heat exchanger 40 containing interior baffles 41 for a staggered flow of the vapors to a vapor outlet 42. The interior of the heat exchanger 40 is equipped with connected closed pipe coils 43 through which a heat exchange medium is passed to effect condensation of a substantial proportion of the solvent 75

vapors. Remaining uncondensed solvent vapor is withdrawn through 42 by vacuum pump 45 and discharged through an additional condenser 46. Solvent condensing in 40 drains into a sump 47 from which it is withdrawn by liquid pump 48 and forced through line 49 to the solvent line 16, so that the solvent is continuously recycled to the chilling system. Remaining solvent condensed in condenser 46 passes by line 50 to line 16. The 5 condensed solvent may be accumulated in a surge tank 51 from which it is withdrawn to line 16 in order to overcome fluctuations in the rates of condensation and supply of pre-chilled solvent. An additional chiller for the solvent may be located in line 16, if desired, although this is not necessary in the arrangement shown. The proportioning of oil mix and pre-chilled solvent may be maintained by suitable proportioning pumps (not shown) in lines 15 and 16 respectively.

10 Flue gas is supplied to the upper portions of each of the flash distillation chambers from a main 55 leading from a source of supply of flue gas under pressure of about say forty pounds per square inch through lines 56, 57 and 58 equipped with shut-off valves 59, 60 and 61 respectively. Each of the flash distillation chambers is also equipped adjacent the upper portion thereof with a vapor off-take 63 provided with a shut-off valve 64 leading to a common vacuum pump 65 of the flue gas recirculation system, said pump serving to return the flue gas under pressure through line 66 to the gas holder (not shown) which supplies main 55. The towers 27, 28 and 29 are also equipped with liquid discharge lines 70, 71 and 72 provided with shut-off valves 73, 74 and 75 respectively, these lines leading to a common line 76 passing through a conventional double pipe chiller 7 where the oil mix is chilled to the final dewaxing temperature. The chilled mix is then supplied to conventional filtering equipment 78 where the wax is separated from the oil, the wax being discharged at 79 and the oil filtrate by line 80. The oil filtrate is forced by pump 81 through line 82 to the connected pipe coils 43 within heat exchanger 40 where it is passed in heat exchange relationship with solvent vapors. The oil filtrate then passes by line 83 to condenser 46 where it passes in heat exchange relationship with uncondensed solvent vapors, and is finally discharged by line 84 leading to conventional stripping equipment not shown.

In operation, the oil mix from tank 17 is passed to one of the flash distillation towers 27-29. Thus, with the valves 25 and 26 closed and valve 24 open, the oil mix will be passed by line 21 to tower 27, and be flashed through the expansion valve and spray nozzle 30 into the upper portion of the tower. Each of the expansion valves and spray nozzles 30-32 is preferably provided with a heating jacket to which hot water or other heating medium is supplied to prevent freezing of wax and clogging of the valve and nozzle. Under the conditions mentioned, only valve 36 of the vapor off-take 33 will be open, valves 37 and 38 being closed. A high vacuum of the order of 5-10 mm. mercury absolute pressure will be maintained within the distillation chamber 27. Employing the mentioned methyl ethyl ketone-benzol as the solvent mixture, a temperature of approximately 10° F. will be maintained within the flash tower, and substantially one volume of solvent will vaporize, leaving the oil mixed with unvaporized solvent in the dilution ratio of approximately 2:1.

As methyl ethyl ketone and benzol boil at substantially the same temperature, the composition of the solvent vapors passing off through outlet 33 will be substantially the same as the composition of the liquid solvent remaining in the oil. 5 Where solvents having substantially different boiling points are employed, such as methyl ethyl ketone-isopropyl ether, it will be apparent that the solvent vapors will be composed mainly of the lower boiling solvent constituent,—in such case 10 mainly of isopropyl ether. It will be readily appreciated that the original dilution of the oil to be dewaxed, and the solvent composition, will be adjusted in accordance with such conditions so as to give the desired proportion of wax anti-solvent and oil solvent in the final chilled mix 15 passing to the filters. This can readily be determined for each particular solvent composition. The vapors passing off through 33 will be largely 20 condensed in the condenser 40 with the result that once the high vacuum and accompanying low temperature are produced within the flash tower 27, this high vacuum and low temperature can be maintained primarily by condensation of the solvent vapors, and only a small vacuum 25 pump 45 will be required in the operation of the system.

When tower 27 has filled to the desired level with oil mix chilled to the temperature mentioned, valves 24 and 36 will be closed and valves 30 25 and 37 opened, so that the oil mix will then be flashed into the second flash tower 28. During continuance of the flashing into the tower 28, valve 59 will be opened to supply flue gas under pressure of the order of about forty pounds per 35 square inch to the top of tower 27, and valve 73 of discharge pipe 70 will be opened so that the oil mix will be forced by the gas pressure from tower 27 through lines 70 and 76, the double pipe chiller 77 where the mix is further chilled to 40 a dewaxing temperature of the order of -15° F., and then to the filters 78.

Following the filling of tower 28 with oil mix to the desired level and the discharge of chilled oil mix from tower 27 to the filters, valves 26 and 45 45 will then be closed and valves 25 and 38 opened so that the oil mix is then flashed into the third tower 29. At this time, valves 59 and 73 are closed and valves 60 and 74 opened so that the accumulated oil mix in tower 28 is then supplied to the chiller 77 and filters 78. This provides for continuous operation of the filters. Just before complete emptying of tower 27 of chilled oil mix, and following closing of valves 59 and 73, valve 64 in line 63 will be opened, so that the 55 large vacuum pump 65 can exhaust tower 27 and produce a high vacuum therein. The vapors so exhausted are returned by pump 65 to the flue gas accumulator in a closed system, so that there is substantially no loss of solvent from the system. During this time, tower 28 is discharging to the filters, and tower 29 is being supplied with 60 fresh oil mix by flash distillation.

At the termination of this portion of the cycle, valves 26, 38 and 64 are closed, and valves 24 and 65 36 again opened, so that oil mix will be supplied once more to tower 27 by flash distillation. At this time, the valves are manipulated so that tower 29 discharges through the chiller 77 to 70 filter 78, while tower 28 is connected to line 63 and vacuum pump 65 by opening its respective valve 64 to exhaust gas therefrom and create a high vacuum therein. The cycle is then repeated in the manner stated, with one tower operating 75

with flash distillation, a second tower discharging to the filters and the third tower exhausting. Manipulation of the valves may be manually controlled, but is preferably accomplished by synchronizing mechanism from a central station or control board with both manual and automatic controls as is well understood.

The dewaxed filtrate coming from the filter 18 at a temperature of around -15° F. is passed 10 by pump 81 through the pipe coils 43 of heat exchanger 40 where it serves to cool and condense solvent vapors from the flash distillation tower, while at the same time the filtrate is warmed to a temperature of the order of +5° F. 15 This filtrate then passes through heat exchange coils of condenser 46 where it serves to cool and condense remaining solvent vapors supplied thereto by pump 45. The filtrate at a temperature of the order of 35° F. then passes to the 20 strippers, where solvent is stripped off in the usual manner.

In place of flashing the oil mix into a high vacuum zone for evaporative cooling in a single stage, the process may be carried out in a plurality of series connected flash distillation stages 25 as diagrammatically illustrated in Fig. 2. As shown therein, the oil mix in the tank 17, corresponding to the tank 17 of Fig. 1, is first expanded through line 86 and expansion valve 87 30 into a tank 88 which may be maintained under an intermediate vacuum equivalent to an absolute pressure of 60 mm. mercury, by a vapor offtake 89 containing pressure reducing valve 90 leading to the condensing equipment and vacuum pump 35 as illustrated in Fig. 1. With a solvent mixture of 50% methyl ethyl ketone and 50% benzol, this will produce a temperature of approximately 60° F. in tank 88. The partially chilled oil mix accumulating in tank 88 is discharged through line 40 91 and expansion valve 92 into tank 93 maintained at an absolute pressure of say 30 mm. mercury by vapor off-take 95. With the solvent combination mentioned, this will produce a temperature of approximately 35° F. in tank 93. 45 The oil mix accumulating in tank 93 then discharges by line 96 through expansion valve 97 into flash tower 27' maintained at an absolute pressure of about 5-10 mm. mercury by vapor off-take 33' containing shut-off valve 36' and 50 pressure reducing valve 98. Three flash towers corresponding to tower 27' may be provided for the cyclic operation described above in connection with the towers 27-29 of Fig. 1. In such 55 case, line 96 will be branched for connection to one or the other of the three towers, with suitable shut-off valves in the various branched connections. The various vapor off-takes 89, 94 and 33' can be connected to a common condensing and vacuum producing equipment, and the different 60 subatmospheric pressures of the flashing stages can be controlled by proper regulation of the pressure reducing valves 90, 94 and 98. In the case of some oils, where flashing in a single stage produces too great a turbulence, ebullition 65 or foaming in the flash tower, the staged flashing may be employed with advantage.

The present invention offers the advantages of reduction in solvent ratio, reduction in size of equipment and installation costs, reduction in 70 chilling and stripping costs and reduction in solvent inventory. The combination of the use of pre-chilled solvent to chill the wax-bearing oil to the temperature of incipient wax precipitation, with evaporative cooling by flash distillation to further chill through the major portion

of the wax precipitation range, enables the chilling operation to be carried out in a manner which produces and preserves desired crystal structure, giving high filtration rates, compact wax cakes which are comparatively free from 5 retained or occluded oil, and a high yield of dewaxed oil, while at the same time enabling the dilution ratio of the incoming charge to be maintained at a comparatively low value of the order of 2:1 or lower.

Obviously many modifications and variations may be made from the present invention without departing from the spirit and scope thereof, and therefore only such limitations should be imposed as are indicated in the appended claims.

I claim:

1. In the dewaxing of wax-bearing mineral oil containing naturally-occurring or added wax crystal modifying material, the method comprising diluting the oil containing wax crystal modifying material with a normally liquid dewaxing solvent comprising wax anti-solvent liquid and oil solvent liquid such that the oil and wax are substantially completely dissolved in the solvent mixture at a temperature of about 100 to 130° F., 20 heating the mixture to a temperature of around 160 to 170° F. to condition the mixture for wax separation, cooling the mixture to about the temperature of incipient wax precipitation, atomizing the cooled mixture in a high vacuum zone in 25 the form of dispersed droplets above the normal liquid level therein such that a substantial portion of the solvent vaporizes to provide evaporative cooling of the mixture with resultant precipitation of the bulk of the wax constituents, 30 withdrawing the evaporatively cooled mixture, and removing the precipitated wax therefrom.

2. The method according to claim 1 in which the normally liquid solvent comprises a low molecular weight aliphatic ketone and an aromatic 40 hydrocarbon.

3. In the dewaxing of wax-bearing mineral oil containing naturally-occurring or added wax crystal modifying material, the method comprising partially diluting the oil containing wax crystal 45 modifying material with a normally liquid dewaxing solvent comprising a wax anti-solvent and an oil solvent such that the oil and wax are substantially completely dissolved in the solvent mixture at a temperature of about 100 to 130° F., 50 heating the mixture to a temperature of around 160 to 170° F. to condition the mixture for wax separation, mixing therewith a further quantity of prechilled solvent liquid mixture to reduce the temperature of the mixture to about that of incipient wax precipitation, atomizing the resulting mixture in a high vacuum zone in the form of dispersed droplets above the normal liquid level therein such that a substantial portion of the solvent vaporizes to provide evaporative cooling 60 of the mixture with resultant precipitation of the bulk of the wax constituents, withdrawing the evaporatively cooled mixture, and removing the precipitated wax therefrom.

4. In the dewaxing of wax-bearing mineral oil 65 containing naturally-occurring or added wax crystal modifying material, the method comprising partially diluting the oil containing wax crystal modifying material with a normally liquid dewaxing solvent comprising a wax anti-solvent 70 and an oil solvent such that the oil and wax are substantially completely dissolved in the solvent mixture at a temperature of about 100 to 130° F., heating the mixture to a temperature of around 160 to 170° F. to condition the mixture for wax 75

separation, cooling the heated mixture to a temperature somewhat above the temperature of incipient wax precipitation, adding a further quantity of prechilled solvent liquid mixture to chill the wax-bearing mixture to a temperature of incipient wax precipitation, atomizing the thus cooled mixture in a high vacuum zone in the form of dispersed droplets above the normal liquid level

therein such that a substantial portion of the solvent vaporizes to provide evaporative cooling of the mixture with resultant precipitation of the bulk of the wax constituents, withdrawing the evaporatively cooled mixture, and removing 5 the precipitated wax therefrom.

EDWIN C. KNOWLES.
